UNITED STATES PATENT OFFICE.

CHARLES HAMMER, OF HOLLIS COURT BOULEVARD, NEW YORK.

BAND-SEALING FRICTION CATCHUP CAP.

Application filed July 7, 1923. Serial No. 650,116.

To all whom it may concern:

Be it known that I, CHARLES HAMMER, a citizen of the United States, residing at Hollis Court Boulevard, in the county of 5 Queens and State of New York, have invented certain new and useful Improvements in Band-Sealing Friction Catchup Caps, of which the following is a specification.

10 This invention relates to band sealing catchup caps, the object thereof being to provide an improved friction catchup cap adapted to be effectively sealed on a container, such as a glass container, by means 15 of a sealing band.

Catchup caps have been made with threads intended to be sealed on a container by means of a sealing band, but it is not possible in these forms of caps to force the cap 20 down by pressure, and then seal it by means of a friction band, since as the caps are provided with threads for rotating the cap on to the neck of the catchup bottle, mechanical pressure cannot be used to force the cap on 25 to the bottle and hold it there during the application of the sealing band. In other words the cap must be rotated on to the bottle and then the sealing band applied. Consequently, the bottle cannot be as effec- 30

tively sealed in the first instance by this rotation, as it can be by mechanical pressure directly applied to the top of the cap, and therefore the object of the present improvement is to provide an improved cap of this 35 description, which can be automatically sealed by mechanical pressure without the necessity of rotating the cap on to the container, and then held sealed by a sealing band, so that when the band is removed the 40 cap can be reused and for this purpose the cap is in the form of a friction cap, which can be readily slipped on and off without the necessity of rotating it on the threads of the bottle.

45 This construction enables the user to see when he purchases the article that if the sealing band is intact the contents have not been tampered with. One of the disadvantages of a threaded catchup cap is that in 50 the repeated pouring of small portions of the contents of the bottle, the catchup accumulates around the threads of the bottle and the cap where it hardens and is effected by the atmosphere becoming dark or black, more or less unsanitary, and also presenting

a messy and unsightly appearance and one that is objectionable to the user, especially as no attempt is usually made in restaurants to cleanse the threads either of the bottle neck or cap because probably this cannot be 60 readily done due to the difficulty of getting into the threads of the cap, and this hardened matter also somewhat interferes with an efficient resealing of the bottle. In the present improvement there are no threaded 65 surfaces for the accumulation of the contents of the bottle since the cap has a comparatively smooth interior surface which can be readily cleansed and can be readily slipped or snapped on and off, and by means 70 of its friction engagement efficiently held on to the bottle after the removal of the sealing band. In the drawings accompanying and forming a part of this specification Fig. 1 is a part sectional view of this improved 75 cap and its sealing band applied to a catchup bottle; Fig. 2 is a perspective view of the cap removed from the bottle and its sealing band; Fig. 3 is a sectional view of the sealing band detached; Fig. 4 is a per- 80

85

Similar characters of reference indicate corresponding parts in the several views.

Before explaining in detail the present improvement and mode of operation thereof, it is desired to have it understood that the invention is not limited to the details 90 of construction and arrangement of parts which are illustrated in the accompanying drawings, since the invention is capable of other embodiments, and the phraseology which is employed is for the purpose of description and not of limitation.

95

This improved catchup cap comprises a top 2 and a long depending cylindrical skirt or flange 3. The cylindrical skirt or flange is usually seamed in some suitable way 8' 100 and in two-piece catchup caps is interlocked with the top by a suitable interlocking seam. The long depending flange terminates at its lower edge in a strengthened edge 4 which is preferably obtained by rolling, curling or beading said lower edge thereby securing protection from rust and unsanitary conditions, as well as preventing the cutting of the hands of the user. The flange is provided with a deformed portion forming an 110

annular band or inwardly extending portion of less diameter than the normal diameter of the cap at each side of said band whereby this band is no greater and is 5 usually slightly less than the diameter of the side sealing face of the container. This band is adapted to frictionally contact with the outer or side sealing surface of the catchup bottle or container throughout an 10 appreciable width of the band whereby it will be held thereon and can be readily snapped on and off the bottle 6, which is provided with a shoulder 7 located relatively remote to the top or upper edge of 15 the bottle. Owing to the deep flange or skirt necessary in catchup caps it is difficult to draw such a cap from one piece of metal and therefore the skirt and top as hereinbefore stated are usually formed separately 20 and interlocked by a suitable seam as 8. Located in the top of the cap is a sealing disc 9 by means of which the bottle is sealed when the cap is in place. In the form of cap shown in Figs. 1 and 2 it is provided 25 with corrugations 10 assisting to reinforce the cap flange and also forming a roughened surface for the handling of the cap. These corrugations are located above the friction sealing surface.

30 In the form of cap shown in Fig. 5 it is provided with a deformed or polygonally formed flange 11 which serves all of the purposes of corrugations and the annular friction band 5, that is to say, these polygonal 35 surfaces 11 extend all around the cap and form practically an impressed continuous band having a frictional engagement with the outer wall of the bottle and also form a gripping means as well as a strengthening 40 means for the flange of the cap.

For locking either form of cap on to the bottle a suitable sealing band 12 is provided, the upper edge of which is bent or turned over the rolled or beaded lower edge of the 45 cap as at 13 while the lower edge 14 of the sealing band is forced or bent inwardly under the shoulder of the bottle, thus effectively sealing the cap on to the bottle. This 50 sealing band is readily separable by the user since its ends may overlap and if preferred be interlocked in some suitable way.

Thus by suitable mechanical pressure applied to the top of the cap, it is forced downwardly on to the bottle to properly seal the 55 contents and then the sealing band is applied, thus locking the cap in place against tampering or premature removal, so that the user upon purchase of the bottle can tell at a glance whether the cap has been removed 60 or not. Upon the removal of the sealing band the cap can be snapped off without rotation and easily replaced and effectively held thereon by the annular friction surfaces or the polygonal surfaces of the cap 65 so that the cap can be readily reused. It

will be observed that there are no threads or similar surfaces adjacent to the open end of the cap for the lodgement of the bottle contents, and consequently this improved cap is more sanitary and more easily applied and removed, while giving as effective a seal as a threaded cap. From the foregoing it will be observed that I have provided an improved catchup cap having a pair of sealing bands, one comprising a preformed 75 annular friction sealing band in the skirt of the cap and the other a detachable sealing band applied to the skirt and to the shoulder of the container so that the two bands initially secure and seal the container, but when the detachable band is removed, the cap can be readily snapped on for reuse and will be by means of the preformed annular friction band not only secured, but sealed on the catchup bottle so as not only to preserve the 80 contents of the bottle but prevent the spilling thereof should the bottle be tipped over. Thus I have provided not only a sanitary catchup cap but a double side sealed catchup cap in the first instance, and upon the removal of the detachable band the cap will subsequently in the reuse thereof effectively seal the contents, and I believe I am the first to provide a snap on double side seal catchup 85 cap.

From the foregoing it will be observed that this improved cap seals the contents at three points to wit, at the top end or mouth of the bottle, at the side by means of the annular friction band and again at the 90 shoulder.

It is to be understood that by describing in detail herein any particular form, structure, or arrangement it is not intended to limit the invention beyond the terms of the several claims or the requirements of the 95 prior art.

Having thus explained the nature of my 100 said invention and described a way of constructing and using the same, although without attempting to set forth all of the forms in which it may be made, or all of the modes of its use, I claim:

1. A reusable double side seal catchup cap 115 adapted for use with a shouldered catchup container and comprising a top having a long depending flange or skirt, said cap having a pair of sealing bands for initially securing and sealing the cap on to a catchup bottle, said sealing bands comprising an annular preformed friction band in the skirt of the cap and smaller than the normal diameter of the skirt, and an annular detachable band applied to the skirt of the cap and to the shoulder of the container, said preformed annular band also securing and sealing the contents of the container on the removal of said detachable band and the subsequent snapping on of the cap.

2. A reusable double side seal catchup cap 130

- adapted for use with a shouldered catchup container and comprising a sealing top having a long depending flange or skirt provided with a strengthened lower edge, said cap having a pair of sealing bands for initially securing and sealing the cap on to a catchup bottle, said sealing bands comprising an annular preformed friction band in the skirt of the cap and smaller than the normal diameter of the skirt and an annular detachable band applied to the strengthened lower edge of the skirt of the cap and to the shoulder of the container, said preformed annular band also securing and sealing the contents of the container on the removal of said detachable band and the subsequent snapping on of the cap.
3. A combined band sealed and snap-on reusable friction cap for catchup containers comprising a top having a long depending flange or skirt provided with an annular impressed preformed friction band of less diameter than the normal diameter of the skirt for engaging the container and a detachable sealing band for initially and additionally securing said cap on the container.
4. A combined band sealed and snap-on reusable friction cap for catchup containers comprising a top having a long depending flange or skirt provided with an annular impressed preformed friction band of less diameter than the normal diameter of the skirt for engaging the container, said skirt having a rolled, beaded or curled lower edge, and a detachable sealing band engaging said rolled edge for initially and additionally securing said cap on the container.
5. A combined band sealed and snap-on reusable friction cap for catchup containers comprising a top having a long depending flange or skirt provided with a rolled, beaded or curled lower edge, said skirt having a polygonal formation forming preformed friction band surfaces having a diameter smaller than the normal diameter of the skirt for engaging the container and a detachable sealing band engaging said rolled edge for initially and additionally securing said cap on the container.
6. A sealed catchup package comprising a catchup container having a shoulder, and a combined band sealing and reusable snap-on friction catchup cap comprising a top and a long depending flange or skirt provided with a rolled, curled or beaded lower edge and an impressed preformed annular friction band of less diameter than the normal diameter of the skirt for engaging the container, and a detachable sealing band engaging said rolled edge and underlapping the shoulder of the container, whereby said cap may be applied under mechanical pressure to force it in the direction of its length to seal the bottle and initially and additionally secured in position by the band, and upon the removal of the sealing band the cap may be reused by snapping it on and off.

Signed at Brooklyn, N. Y., this 5th day of July 1923.

CHARLES HAMMER.
